5 Claims. (Cl. 252—96)

ABSTRACT OF THE DISCLOSURE

A detergent composition comprising a water-soluble organic anionic (soap or non-soap) or nonionic detergent compound, a water-soluble inorganic oxygen-releasing per compound, a fluorescer which is a derivative of 1,3-diphenyl- Δ^2 -pyrazoline, and diethylene triamine pentaacetic acid to reduce substantially the loss of fluorescer due to the oxidative degradation thereof by the per compound.

This invention relates to detergent compositions which contain a synthetic detergent and/or a soap, an oxygen-releasing per compound, and a fluorescent brightening agent which is a derivative of 1,3-diphenyl Δ^2 -pyrazoline. It is especially concerned with particulate compositions.

Although substituents in the phenyl groups of the diphenyl pyrazoline are not of importance to the mechanism of the invention the fluorescers of particular interest are of the following formula:

wherein X and Y are H, lower alkyl, aryl, $—CF_3$, $—F$, $—Cl$, $—Br$, $—CN$, $—SO_2NH_2$, $—CO_2R$, $—SO_2R$, $—NHCOR$, $—CO_2NR_1R_2$ or $—SO_2NR_1R_2$ where R is H, lower alkyl or aryl; and R₁ and R₂ are hydrogen, lower alkyl or aryl.

Hitherto, these detergent compositions have been unstable both in storage and in use. They have shown a loss in fluorescer content in storage and in use with consequential loss in fabric whitening effect. This loss has been found to be due to the oxidation of the fluorescer by the per compound to give the corresponding pyrazole which is then further oxidised.

This invention provides a synthetic detergent and/or soap composition in which the loss of fluorescer is reduced.

Accordingly the present invention provides a composition comprising a synthetic detergent and/or a soap, a brightening agent which is a derivative of 1,3-diphenyl Δ^2 pyrazoline, an oxygen releasing per compound and, as an additive to reduce the loss of the pyrazoline, diethylene triamine penta acetic acid.

Particularly convenient pyrazoline fluorescers are 1-p-sulphonamidophenyl-3-(p-chlorophenyl) Δ^2 -pyrazoline (referred to hereafter as A), 1-(p-carboxymethyl phenyl)-3-(p-chlorophenyl)- Δ^2 -pyrazoline (referred to hereafter as B) and 1-(m-chlorophenyl)-3-(p-acetylaminophenyl)- Δ^2 pyrazoline (referred to hereafter as compound C). Such fluorescers may be present in the detergent compositions at concentrations varying from 0.01% to 0.05%.

Suitable per compounds are alkali metal perborates and alkali metal per carbonates, e.g. sodium perborate and sodium percarbonate. Hydrogen peroxide may be used in liquid formulations.

These may be present in the detergent compositions at concentrations varying from 1-50%, preferably 10-20% by weight of the total composition.

The concentration of diethylene triamine penta acetic acid (DETPA) to be used in the compositions depends on the degree of stabilisation required of the composition, the amount and stability of the per compound present and the storage conditions likely to be encountered.

The compositions lose their fluorescer more rapidly when stored under climatic conditions of elevated temperature and humidity and consequently products to be stored under such conditions may require a higher level of DETPA than those to be stored under milder conditions. Useful levels of DETPA range from 0.01% to 2% on the final composition. The levels usually found to be successful are 0.1-1% by weight of the composition.

DETPA has the advantage of compatibility with detergent compositions and does not affect the physical properties or the washing performance of the detergent composition to which it is added.

25 The synthetic detergent, if present, is conveniently an anionic compound, for example an alkyl aryl sulphonate, especially sodium dodecyl benzene sulphonate, an alkyl sulphate, or an alkyl glyceryl ether sulphonate. This is present in amount varying from 5 to 50% by weight of the composition. With the higher amounts of synthetic detergent, less additive may be found necessary for adequate stabilisation to storage.

25 A nonionic detergent may be used for example, an alkylene oxide condensate of an alcohol or phenol, such as tallow alcohol/9 ethylene oxide or nonyl phenol/9 ethylene oxide condensates.

In compositions in which the active is provided by soap, suitable soaps are the sodium, potassium or ammonium salts of tallow fatty acids or coconut fatty acids or the blends customary in the production of particulate soap-based products.

These are present in amount 5 to 75% of the total composition.

45 The invention is also concerned with compositions in which both synthetic detergent and soap are present.

The usual ingredients of detergent compositions may be present, viz. builders, perfume, etc. Further fluorescer components may be added, e.g. the cotton fluorescers of the triazinyl stilbene type.

50 The effect of the DETPA in reducing the loss of fluorescer from a typical perborated detergent composition is shown below.

Example 1

55 Detergent products were prepared from a slurry of 200 g. active detergent (sodium dodecyl benzene sulphonate), 350 g. of sodium tripolyphosphate, 270 g. of builder salt and 400 g. of water. To this slurry was added fluorescer, and DETPA in the amounts shown in the following table. The resultant slurry was then drum dried and a portion of each power except the control portion was dry

60 mixed with 10% sodium perborate. The powders were stored in laminated cardboard containers in a room held at 20° C. and 90% relative humidity. Periodically the powders were removed and their fluorescer contents were estimated by washing a piece of non-fluorescent nylon fabric in an aqueous solution of the powder for 5 minutes at 60° C. From the fluorescence measurements of the fabrics it was possible to estimate the amount of fluorescer remaining in the stored powder. The results obtained for

these powders is given below and compared with a powder without DETPA.

TABLE I

Percent by weight of total composition	Percent A remaining on storage			
	0 days	14 days	38 days	70 days
0.08% A (as control)	100	96	95	90
0.08% A, 10.0% sodium perborate	100	68	26	1
0.08% A, 10.0% sodium perborate, 1.0% DETPA	100	100	93	90

Example 2

15

Similar results were obtained from powders of the foregoing slurry, spray-dried and stored at 20° C. and 90% R.H., as shown below:

TABLE II

Percent by weight of total composition	Percent original B remaining on storage		
	0 days	8 days	14 days
0.025% B	100	-----	95
0.025% B, 10.0% sodium perborate	100	50	12
0.025% B, 10.0% sodium perborate, 0.10 DETPA	100	89	74

Example 3

Under less humid storage conditions 23° C. and 70% R.H. the decomposition rates of the unstabilised product was slower but a similar stabilising effect was observed 35 as follows:

TABLE III

	Percent B remaining on storage			
	0 days	28 days	70 days	160 days
.025 B	100	98	98	89
.025 B, 10.0% sodium perborate	100	68	30	9
.025 B, 10.0% sodium perborate 0.10 DETPA	100	95	86	75

Further examples of fluorescer stabilisations in spray dried products based on the above mentioned slurry form- 50 ualisation:

Example 4

TABLE IV

	Percent B remaining on storage at 23° C., 70% R.H.		
	0 days	70 days	160 days
0.065% B	100	100	95
0.065% B, 10% sodium perborate	100	60	34
0.065% B, 10% sodium perborate, 0.1% DETPA	100	92	84

Example 5

TABLE V

	Percent C remaining on storage		
	0 days	28 days	70 days
.025% C	100	100	97
.025% C, 35% sodium perborate	100	35	10
.025% C, 35% sodium perborate, 1.5% DETPA	100	92	85

Example 6

TABLE VI

	Percent B remaining after storage at 23° C., 70% R.H.		
	0 days	28 days	70 days
0.065% B	100	98	98
0.065% B, 50% sodium perborate	100	72	60
0.065% B, 5.0% sodium perborate, 0.1% DETPA	100	95	92

Example 7

TABLE VII

	Percent B remaining after storage at 23° C., 70% R.H.		
	0 days	28 days	70 days
0.065% B	100	100	95
0.065% B, 15% sodium percarbonate	100	45	30
0.065% B, 15% sodium percarbonate, 0.5% DETPA	100	80	76

Example 8

TABLE VIII

	Percent B remaining after storage at 23° C., 70% R.H.				
	0 days	14 days	25 days	67 days	82 days
0.08% B	100	100	95	-----	95
0.08% B, 10% sodium perborate	100	81	68	20	17
0.08% B, 10% sodium perborate, 0.5% DETPA	100	90	90	89	89

Other detergent compositions to which DETPA can be added according to the invention are typified by the following examples:

in Table IX in which its stabilisation effect is compared with the effects of EDTA and Trilon A (nitrilo triacetic acid), using the spray dried slurry of Example 2.

TABLE IX

	Storage conditions 23° C., %R.H.		
	0 days	70 days	100 days
0.025% A	100	98	98
0.025% A, 10% sodium perborate	100	20	12
0.025% A, 10% sodium perborate, 0.5% DETPA	100	91	87
0.025% A, 10% sodium perborate, 0.5% EDTA	100	80	70
0.025% A, 10% sodium perborate, 0.5% Trilon A	100	32	17

Example 9

Sodium dodecyl benzene sulphonate	25
Anhydrous soap	4
Sodium tripolyphosphate	25
Sodium sulphate	10
Sodium silicate	8
Sodium perborate	15
Fluorescer B	0.08
DETPA	0.2
Water, perfume, cotton substantive fluorescer balance.	50

Example 10

Anhydrous soap	50
Sodium carbonate	8
Sodium silicate	8
Sodium perborate	10
Fluorescer A	0.03
DETPA	0.1
Water, perfume, cotton substantive fluorescer balance.	55

Example 11

Tallow alcohol 25EO	12
Anhydrous soap	3
Sodium tripolyphosphate	35
Sodium silicate	8
Sodium sulphate	10
Sodium perborate	15
Fluorescer C	0.05
DETPA	0.5

Example 12

That DETPA is effective to a surprising degree in bringing about such stabilisations is illustrated by the results

Example 13

A typical liquid formulation is:

	Percent
Sodium dodecyl benzene sulphonate	10.0
Potassium pyrophosphate	20.0
Sodium xylene sulphonate	4.0
Fluorescer A	0.03
DETPA	0.20
Hydrogen peroxide	4.0

In the foregoing examples, potassium perborate or percarbonate may replace the sodium perborate or percarbonate respectively.

What is claimed is:

1. A detergent composition consisting essentially of (1) a water-soluble organic detergent compound selected from the group consisting of (a) from about 5% to about 50% by weight of (a₁) a nonionic detergent and (a₂) an anionic non-soap detergent and (b) from about 5% to about 75% by weight of a soap, (2) from about 1% to about 50% by weight of a water-soluble inorganic oxygen-releasing per compound, (3) from about 0.01% to about 0.5% by weight of a fluorescer which is a derivative of 1,3-diphenyl-Δ²-pyrazoline selected from the group consisting of 1-(p-sulphonamidophenyl)-3-(p-chlorophenyl)-Δ²-pyrazoline, 1-(p-carboxymethyl phenyl)-3-(p-chlorophenyl)-Δ²-pyrazoline and 1-(m-chlorophenyl)-3-(p-aceylaminophenyl)-Δ²-pyrazoline, and (4) from about 0.01% to about 2% by weight of diethylene triamine pentaacetic acid.

2. The detergent composition as defined by claim 1 wherein the water-soluble organic detergent compound is selected from the group consisting of nonionic deter-

gents and anionic non-soap detergents and is present in an amount from about 5% to about 50% by weight.

3. The detergent composition as defined by claim 1 wherein the water-soluble organic detergent compound is soap and is present in an amount from about 5% to about 75% by weight.

4. The detergent composition as defined by claim 1 wherein the water-soluble inorganic oxygen-releasing per compound is selected from the group consisting of hydrogen peroxide, sodium and potassium perborates, and sodium and potassium percarbonates and is present in an amount from about 10% to about 20% by weight.

5. The detergent composition as defined by claim 1 wherein the diethylene triamine pentaacetic acid is present in an amount from about 0.1% to about 1% by weight.
